UNITED STATES PATENT OFFICE

SAMUEL PERLA, OF BROOKLYN, NEW YORK

LIGHTING FIXTURE PART

Application filed January 10, 1930. Serial No. 419,883.

The present invention relates to lighting fixture parts, and is more particularly directed toward the manufacture of cast lighting fixture arms having receptacles to receive 5 glass plates.

In Design Patent 80,570 for chandelier arm, granted February 25, 1930 on the joint application of Rasmus R. Hellyvik and Samuel Perla for design patent, there is shown a 10 sign for arms adapted to be mounted in chandeliers. These arms are in a vertical plane and are provided with an upwardly opening receptacle to support a vertical glass panel.

15 The present invention relates to the manufacture of such arms, and it is, therefore, an object of the present invention to provide a fixture part adapted for supporting such glass panels and having the parts so arranged 20 that they can be conveniently formed in two-part permanent molds.

Other and further objects will appear as the description proceeds.

The accompanying drawings show, for 25 purposes of illustrating the present invention, one of the many possible embodiments in which the invention may take form, it being understood that the drawings are illustrative of the invention rather than limiting the 30 same.

In these drawings:

Fixture 1 is a fragmentary elevational view of a lighting fixture arm;

Figure 2 is a section on the line 2—2 of 35 Figure 1;

Figure 3 is a fragmentary sectional view on the line 3—3 of Figure 1; and

Figure 4 is a sectional view through the 40 mold for casting the arm and showing the arm in section along the line 4—4 of Figure 1.

Where the arm is of the design shown in the patent application above referred to, it has an upwardly extending portion indicated at 10 in Figure 1 herein, as well as a horizontally extending portion as indicated at 11. Between these two portions is a grille 12 having front or left handed parts 12a and rear or right handed parts 12b.

It will be apparent from the drawings that 50 the grille parts 12a and 12b are so spaced that

their adjacent faces are separated to provide room for a glass panel 13. The cross section of these grille parts may be any shape which can be conveniently molded, and they may be provided with ornament, as indicated.

In order to provide more bearing surface for the glass and improve the appearance of the fixture part, the end members 14 and 15 of the grille are provided with narrow flanges 16. All these flanges are connected with one set of grille parts, such as the parts 12b. They are not continuous, but have gaps 17 opposite the other grille parts 12b.

The mold employed in making this casting is shown in Figure 4. It is a two-part permanent mold made, for example, of bronze, and provided with interior cavities to form the casting to shape. The mold half 20 at the left of Figure 4 is designed for the front part of the casting, i. e., all parts below the plane A—A of Figures 2 and 3, except such parts as are between the end members 14 and 15 of the grille. The mold half 21 at the right of Figure 4 is similarly designed for the parts above the plane A—A of Figures 2 and 3, except the grille parts between the end members 14 and 15.

Where the grille is to be formed, the inner face of the mold half 20 is displaced to the right, as indicated at 20a, and the inner face of the mold half 21 is displaced to the left, as indicated at 21b. These parts of the molds form the adjacent faces of the grille parts, separating them to form the passage way for the glass. The parts 21b of the mold half 21 also form the gaps 17 in the flanges 16, thereby allowing the casting to be removed from the mold. The mold is drafted, as will be apparent from the drawings.

The fixture arms made in the manner above described in detail may be used with or without the glass panel, and may be made without resort to complicated molds ordinarily employed where undercuts are required. The grille arrangement is able to support the glass, form appropriate ornament, and, at the same time, imposes no casting difficulties.

It is obvious that the invention may be embodied in many forms and constructions, and I wish it to be understood that the particu- 100

lar form shown is but one of the many forms. Various modifications and changes being possible, I do not limit myself in any way with respect thereto.

What is claimed is:

- 6 1. A cast lighting fixture part having a grille formed of end members and a plurality of cross members arranged in staggered relation and spaced to accommodate a glass panel.
- 10 2. A cast lighting fixture part having a grille formed of end members and a plurality of cross members arranged in staggered relation and spaced to accommodate a glass panel, the side members having narrow flanges adjacent the cross members to one side of the space, the flanges having gaps opposite the cross member on the opposite side of the space.
- 15 3. A cast lighting fixture part having side members the adjacent faces of which are provided with discontinuous flanges in one plane, a set of cross members connecting the side members and disposed in the plane of the flanges, and a second set of cross members connecting the side members and located opposite the gaps in the flanges and in a plane spaced from that of the flanges to provide a space for a glass panel.
- 20 4. A lighting fixture part in the form of an integral casting having side members and cross members arranged in staggered relation and spaced to accommodate a glass panel, the side members and cross members being shaped to allow for draft in opposite directions from a medial plane, except opposite each cross member where the draft extends across the medial plane to the plane of the cross member.
- 25 5. A lighting fixture part in the form of an integral casting having side members and cross members arranged in staggered relation and spaced to accommodate a glass panel, the cross members and the portions of the side members to one side of the medial plane of the casting being drafted in one direction, the cross members and portions of the side members on the opposite side of the medial plane being drafted in the opposite direction, except that as to the portions of the side members opposite the cross members, they are drafted beyond the medial plane to the plane of the cross members.
- 30 6. The lighting fixture part of claim 5 characterized in that it is provided with interrupted flanges in the plane of one set of cross members, the side members being drafted to the flanges.

SAMUEL PERLA.
